United States Patent Office

Des. 215,098

Patented Sept. 2, 1969

215,098

CARREL

Lucile M. Wilcox, Bellevue, Wash., assignor to Fred Bassetti & Co./Architects, Seattle, Wash.

Filed May 31, 1968, Ser. No. 12,190

Term of patent 3½ years

Int. Cl. D6—01

U.S. Cl. D33—11

Fig. 1.

Fig. 2.

Fig. 3.

FIGURE 1 is a front perspective view of a carrel showing my invention;

FIGURE 2 is a side elevational view; and

FIGURE 3 is a rear view thereof.

The side not shown is a mirror image of the side shown.
I claim:

The ornamental design for a carrel, as shown and described.
